[57] ABSTRACT

A feed tube extends downwardly into a hopper, preferably a vacuum hopper wherein vacuum pressure is created within the hopper to draw material through the feed tube thereinto, and it is preferably a split hopper having at least two sections filled with separate material at a predetermined ratio. The lower end of the feed tube includes an arrangement such as openings in the tube itself and a relatively rotatable surrounding sleeve for varying the upper limit of lateral through openings through the side of the feed tube. When the material in the hopper reaches the said upper limit and hence covers the through openings, the vacuum will no longer be communicated to the interior of the feed tube and hence the flow of material therethrough will terminate. Consequently, the relative positions of the inner tube and the surrounding sleeve determine the amount of material delivered to the section of the hopper associated with that feed tube.

HOPPER WITH VARIABLE LEVEL HOPPER FEED TUBE

BACKGROUND OF THE INVENTION

This invention relates to vacuum hoppers, and in particular it relates to a new and improved feed tube for such a hopper, which feed tube has the capability of varying the level of the material delivered through the feed tube to the hopper. A vacuum hopper of the type with which the present invention is concerned is illustrated and described in U.S. Pat. No. 3,309,146. This type of hopper is normally split into two sections each of which is filled from a separate source and both of which are emptied through a common bottom gate. A suitable means such as a motor-blower creates a vacuum within the entire hopper, and this vacuum is used to draw material through feed tubes from separate sources to the two separate sections of the hopper. One particular application of this type of hopper is in the plastic industry where it is often desirable to supply at least two different materials such as virgin and regrind material in a fixed volume ratio to a machine for processing or forming. One material such as virgin material is supplied to one side of the hopper while the other material such as the regrind material is supplied to the other side of the hopper. The volume delivered to each of the two sides is carefully controlled in accordance with a predetermined ratio therebetween. After the two sides have been filled to the appropriate levels, the common gate is opened and all of the material in both sides is discharged into a common receiving means for further processing.

Various means are known for supplying the predetermined amounts of material to the two sections of the hopper. As indicated above, in this type of arrangement, the vacuum created within the hopper draws the material through the feed tubes. Consequently, when the material in a given section of the vacuum hopper fills up to a level so as to cover the opening from the feed tube to the hopper, the vacuum is no longer communicated back through the feed tube and hence the flow of material through the feed tube is terminated. This may be sensed for immediately cutting off the motor-blower. In the said U.S. Pat. No. 3,309,146, the feed tube in one section of the vacuum hopper is at a fixed height while the lower end of the feed tube in the other section of the hopper is vertically adjustable. In this manner, the height of the material in the second section can be varied, and the feed tube will be at a height so as to terminate material flow therethrough at a level which will provide the proper ratio to the fixed height of material in the first section.

While these and other known arrangements for delivering material into the various sections of a split vacuum hopper are satisfactory in that they accomplish the purpose, they also suffer from certain disadvantages such as complexity and high cost. Thus, there exists a continuing need for new and improved feed tube arrangements of the present type which are efficient but yet more simplified than those known heretofore.

SUMMARY OF THE INVENTION

Thus, it is a purpose of the present invention to provide a new and improved feed tube of the type for delivering material into a vacuum hopper and concurrently determining the level of the material delivered thereinto.

This purpose of the present invention is achieved by providing a feed tube which extends downwardly into its respective vacuum hopper section, the tube including openings along the side thereof and means for varying the vertical height of these openings without changing the vertical level of the feed tube itself. Since material will flow through the tube into the hopper until the uppermost extent of the openings are covered, it follows that by simply varying the vertical level of the upper limit of the openings, one can vary the level of material delivered into the hopper before the flow is terminated (by terminating communication of the vacuum pressure into the feed tube).

In accordance with a preferred embodiment of the invention, the feed tube itself forms at its lower end an inner tube which is surrounded by an outer sleeve. Openings are made in the side of the inner tube and in the side of the outer sleeve. These openings are related to each other such that by turning one of the said sleeve and inner tube relative to the other, the vertical position of the overlap of the two cutouts can be varied. In a preferred arrangement, the opening through the feed tube will initially be formed at the lower end of the side thereof and upon further relative rotation of the two members, the opening through the feed tube will remain continuous, enlarging in size and simply moving up the side of the feed tube. In other arrangements, the opening can be of a relatively fixed size, this fixed size through opening moving up the side of the feed tube as the members are rotated relative to each other.

Normally, the inner tube will form a part of the continuous conduit back to the source and this will be fixed while the outer sleeve is mounted so as to rotate about the inner tube. Indicia means may be provided on the inner tube and outer sleeve to visually indicate the exact position of the opening, and hence also the level to which the material will fill in the hopper.

The openings in the inner tube and the outer sleeve can take various forms. In accordance with a first embodiment, one member may include downwardly outwardly diverging slots while the other member includes parallel sided slots, the width being equal to the smallest width of the said diverging slots in the other member. With this arrangement, as the straight sided slots gradually start to overlap the diverging slots, the through opening gradually enlarges in size and moves up the side of the feed tube. A similar result can be obtained using a helical row of separate openings on one member and enlarged cutout on the other member which diverges on one side at an angle equal to the helical angle and is parallel to the axis of the feed tube on the other side. With this arrangement, the helically arranged ports overlap with the larger area on the other member one at a time, starting with the lowermost cutout and then moving upwardly; but as each next cutout is exposed, the cutouts beneath it remain exposed.

In other embodiments, the opening through the feed tube can remain of the same size and move gradually up the side of the tube as the inner tube and sleeve are relatively rotated. This may be accomplished, for ex-

ample, by providing on the tube members helical slots or helical rows of openings extending up and about the tube members at the same pitch but in the opposite direction.

Various modifications may be made for the purpose of making fine adjustments after an initial setting of the inner tube and outer sleeve. For example, in the embodiments using separate cutouts rather than continuous slots, one of the two members may be arranged to move vertically (axially) relative to the other so as to vary the extent of the uppermost opened cutout; or alternatively, a further sleeve or the like may be provided so as to partially cover the uppermost open cutout.

Thus, it is an object of the invention to provide a new and improved feed tube for use in a vacuum hopper.

It is another object of this invention to provide, for use in a vacuum hopper, a new and improved feed tube which permits variation of the material delivered into its respective section of the hopper in a highly simplified manner.

It is still another object of this invention to provide, for use in a vacuum hopper, a feed tube having openings in the side thereof, the vertical position of which openings can be varied without changing the vertical position of the feed tube itself, to thereby control the level of the material delivered into that respective section of the vacuum hopper.

It is still another object of this invention to provide, for a vacuum hopper, a feed tube having relatively rotatable inner tube and outer sleeve members, these two members having openings therethrough, and the vertical extent of the openings being varied upon relative rotation of the members.

Other objects and the advantages of the present invention will become apparent from the detailed description to follow, together with the accompanying drawings.

BRIEF DESCRIPTION OF THE DRAWINGS

There follows a detailed description of preferred embodiments of the invention which are to be read together with the accompanying drawings which are provided for illustrative purposes only.

FIG. 1 is a schematic side elevation view of a split vacuum hopper including feed tubes constructed in accordance with the features of the present invention.

FIG. 2 is an enlarged view, partially in section and partially in side elevation of either of the feed tubes of FIG. 1.

FIG. 3 is a development of the portions of the feed tube of FIG. 2 with the inner tube shown in dotted lines and the outer sleeve superimposed thereon (in the closed position of the feed tube) in dotted lines.

FIG. 4 is a plan view of FIG. 2.

FIG. 5 is a side elevation view similar to FIG. 2 showing another embodiment of a feed tube of the present invention.

FIG. 6 is an enlarged development view of the inner tube and outer sleeve of FIG. 5, with the outer sleeve shown in solid lines and the inner tube superimposed thereon in dotted lines, the members being shown in the closed position of the feed tube.

FIG. 7 is a development view similar to FIGS. 3 and 6 showing another embodiment of the invention with the inner tube shown in solid lines and the outer sleeve superimposed thereon in dotted lines in the closed position of the feed tube.

DETAILED DESCRIPTION OF THE PREFERRED EMBODIMENT

Referring now to the drawings, like elements are represented by like numerals throughout the several views.

FIG. 1 illustrates schematically a split chamber vacuum hopper 10 having a pair of chambers 10a and 10b separated by a divider plate 11. As explained in the said U.S. Pat. No. 3,309,146, the two chambers 10a and 10b are filled with different materials such as for example virgin and regrind materials, respectively, when utilizing the vacuum hopper in the plastic forming industry. The important factor is the volume ratio of the two different materials after the delivery of those materials has been completed and the bottom gate 12 is opened by pivoting the same about pivot axis 12a for discharging all of the material in chambers 10a and 10b into a common receptacle.

Also shown in FIG. 1 is a feed tube 15 extending downwardly into each of the chambers 10a and 10b, each feed tube including an inner tube 16 which is generally fixed and which continues to the source of material being delivered to the chambers and an outer sleeve 17. This outer sleeve 17 is preferably rotatable relative to the fixed inner tube 16. Referring momentarily to FIGS. 2 and 4, the sleeve 17 includes a collar 18 fixed thereto which may rest loosely on the top 13 of the hopper 10 so that it can be turned relative to the tube 16. The tube 16 may include a collar 19 fixed thereto to rest on the collar 18. Also, as shown in FIG. 4, indicia means 30 and 31 may be provided on the rotatable and fixed collars 18 and 19, respectively, so as to indicate the degree of rotational movement of the sleeve 17 relative to the fixed tube 16. A motor-blower

14 is shown schematically in FIG. 1 communicating with the chambers 10a and 10b. As explained in the said U.S. Pat. No. 3,309,146, the most important purpose of this type of apparatus is to establish the proper ratio between the two materials in the two different chambers (as opposed, for example, to the absolute amount of the materials). Consequently, as in the said patent, it is feasible to utilize in one chamber a feeding means which always feeds to a constant level and then to use the variable feeding means of the present invention in only the other chamber. However, there are times when it is preferable to control the volume in both levels so as not to always be restricted to a fixed level in one of the two chambers, and hence there is some advantage in having a variable level feed tube in both chambers. Consequently, in the illustrated embodiment, a feed tube is provided in each of the two chambers 10a and 10b.

In the operation of a vacuum hopper of the present type, the hopper 10 is generally enclosed and the interior thereof is evacuated by a motor-blower 14, thus creating a vacuum within the chambers 10a and 10b. This vacuum is communicated through the open bottom of the feed tubes 15 through the interiors thereof all the way back to the source of material where this pressure differential causes material to flow through the tubes 16, through the feed tubes and downwardly into the chambers 10a and 10b. Consequently, it will be understood that when the opening or openings at the lower end portion of the feed tubes 15 are covered, the vacuum pressure within the chambers 10a and 10b can no longer be communicated to the interior of the tubes 16,

and hence the material stops flowing therethrough. At this point the motor-blower is of course shut off so that material will not flow again into the chambers as the material is being discharged through the opened gate. After the material has been discharged, and the gate 12 closed, a new cycle may commence.

In accordance with a main feature of the present invention, lateral openings are provided in the side of the tube 16 and the outer sleeve 17, the pattern of openings being such that as the sleeve 17 turns about tube 16, different portions of the two sets of openings overlap, thereby varying the position, and most importantly the vertical position, of the complete opening through elements 16 and 17, this complete opening constituting a through opening for communication of the vacuum pressure to the interior of tube 16.

A preferred embodiment of the present invention is illustrated in detail in FIGS. 2-4. The bottom of the feed tube 15 is of course open so that material can flow directly through the tube 16 and directly out the end of feed tube 15 as it fills the major portion of the respective chamber beneath the feed tube. In this particular embodiment, the outer sleeve 17 includes a pair of straight sided slots 25 and 26 and the inner tube 16 includes a pair of downwardly diverging slots 27 and 28. As illustrated in the figures, the side of the feed tube 15 is completely closed since the slots 25 and 26 do not overlap the slots 27 or 28. However, referring to FIG. 3 which shows the member 16 and 17 in development view and superimposed on each other, as the member 17 is moved (to the right in FIG. 3), the edge 25a of slot 25 will cross the inclined (actually helical in the curved tube) edge 27a of the slot 27 and the greater the angle of turning, the greater the overlap between slots 25 and 27. Also, of course the upper extent of the through opening formed by the overlap rises upwardly. Thus, by turning the member 17 relative to the member 16, the upper extent of the through opening can be raised, thus raising the level to which the material will be delivered before the delivery thereof is terminated. Edges 26a and 28a of slots 26 and 28 operate in the same manner as described with respect to edges 25a and 27a. Thus, only a single set of overlapping slots need be provided. However, an advantage of providing a second set of slots diametrically opposed from the first set of slots is that it aids in equalizing the distribution of the material passing through the lateral openings after the material has covered the bottom of the feed tube 15. This might be especially important if one of the two through openings is adjacent a wall of the hopper. Also, a single opening could possibly become plugged while this would be less likely with a plurality of through openings.

FIGS. 5 and 6 illustrate another embodiment of the invention. For convenience, only the portion below the top 13 of the hopper is shown in these figures. In this embodiment the inner tube 116 includes a plurality of cutouts 50-54 arranged spirally along a helical path on the inner tube 116. These cutouts are not visible in FIG. 5 because this figure shows the feed tube in the position with none of the openings of the two members 116 and 117 overlapping. The opening in the outer sleeve 117 is generally of a downwardly diverging shape. One side of this opening, which is visible in FIG. 5 and which is shown at the left-hand side of FIG. 6, is formed by a straight vertical edge 39 from which project a plurality of fingers 40-44, the spaces between

these fingers being horizontally aligned with respective ones of the cutouts 50-54. The opposite side of the opening in the sleeve 117, which side is partially visible in FIG. 5 and completely visible at the right-hand side of element 117 in FIG. 6 comprises a set of steps 45-49 which are arranged to cover respective ones of the cutouts 50-54 in the completely closed position as illustrated.

In the operation of the embodiment, sleeve 117 rotates in a direction corresponding to movement to the right in FIG. 6 while tube 116 remains fixed. Upon initial rotation, the cutout 50 will cross the edge 39 and communicate with the space beneath finger 44 thus providing a lower through opening. Upon further movement of sleeve 117, the cutout 51 will communicate with the space between fingers 43 and 44. This will continue until the cutout 54 communicates with the space between fingers 40 and 41. With the present arrangement, it will be noted that as each new higher cutout communicates with the space to the left of edge 39, all of the cutouts beneath it remain exposed.

In both of the embodiments of FIGS. 1-4 and 5-6, as the through opening or openings move up the side of the feed tube, the lower openings or the lower part of a single opening remains exposed. This is a preferred arrangement since it provides the advantage that since the material flowing through the tube will seek the lowermost opening, as the hopper is filled, after the lower end of the tube has been covered, the spiral disposition of the lower openings or opening portions will aid in distributing material generally about the chamber.

However, the invention is also applicable to arrangements wherein the lateral through opening remains of an essentially constant size and moves up the side of the feed tube as the sleeve is rotated. FIG. 7 illustrates schematically two possible structures for operating in this manner. In this case, the fixed feed tube 216 and the rotatable outer sleeve 217 may be provided with either opposite hand equal pitch helical slots 60 and 61 which form through openings as the edges 60a and 61a of the slots overlap or alternatively these slots can be replaced by rows of spirally arranged openings, the rows being of equal pitch and in an opposite direction, and of course the openings in each row corresponding vertically with an opening in the other row. Such openings are illustrated schematically at 62 and 63 for the elements 216 and 217, respectively, in FIG. 7.

The present invention also includes the provision of means for effecting a fine adjustment of the through openings. This would be particularly advantageous when using an embodiment having separate cutouts rather than continuous slots. For example, referring to the embodiment of FIGS. 5 and 6, when a given cutout of the cutouts 50-54 constitutes the uppermost exposed cutout, it may be desirable to change the vertical location of the upper end of that through opening without moving to a different cutout. This can be accomplished in several ways. Firstly, one of the members 16 and 17 can be made to move vertically relative to the other. For example, the collar 19 can engage a longitudinal groove in the tubes 16 to move vertically away from the collar 18, thus permitting movement of the collar 18 upwardly along the tube 16. Similarly, the inner tube 16 can be moved vertically relative to the outer sleeve 17. Alternatively, a further sleeve in addition to the elements 16 and 17 can be provided on the feed tube, which additional element could be spaced

and arranged to cover the uppermost opening and move vertically relative to the members 16 and 17. For example, in the embodiment of FIGS. 5 and 6, a plate could be provided on the exterior of element 17 extending circumferentially only for the length of the fingers 40-44. This would be sufficient for covering the upper portion of the uppermost exposed cutout. Alternatively, a further sleeve could be provided having openings identical to the openings of either one of the members 16 or 17 and movable relative to both of them. It will be understood that these modifications are equally applicable to all of the described embodiments.

Although not illustrated or described in detail, it will be understood that suitable control means would normally be provided. For example, when both of the chambers 10a and 10b were filled so as to cut off the communication of vacuum with the interior of the tube 16, a timer or a pressure switch could cut off the motor-blower 14 and open the gate 12, and after the gate 12 closed, the cycle could begin again.

Although the invention has been described in considerable detail with respect to a preferred embodiment, it will be apparent that the invention is capable of numerous modifications and variations apparent to those skilled in the art without departing from the spirit and scope of the invention.

I claim:

1. An enclosed vacuum hopper having pump means for creating a vacuum pressure therein, a feed tube extending downwardly into the hopper to be subjected to the vacuum pressure in the hopper to move material through the feed tube into the hopper, said feed tube including means defining lateral through openings in the side thereof near the lower end thereof for communicating the vacuum pressure to the interior of the feed tube, and means for varying the vertical position of the lateral through openings while maintaining the lower end of the feed tube at a given vertical position within the hopper.

2. A hopper according to claim 1, the lower end of the tube comprising an inner tube member and an outer sleeve member, each member having lateral openings in the sides thereof, and said varying means including means for rotating one of the members relative to the other to vary the relative position of the sleeve member and the inner tube member openings.

3. A hopper according to claim 2, including indicia means on said sleeve and inner tube for indicating the position of one relative to the other.

4. A hopper according to claim 2, wherein the opening in one of said members comprises at least one slot diverging from an upper edge to a lower end at the lower end of that member, and the opening in the other member comprising a slot extending from an upper edge to the lower end of that member at a divergence angle less than that of the first said member, such that when the two members are turned relatively to overlap the slots, the upper extent of the through opening moves upwardly away from the lower end while the opening remains open beneath said upper extent.

5. A hopper according to claim 4, wherein the slot in the first said member has at least one helical edge and the slot in the said other member includes a pair of straight parallel sides parallel with the axis of the feed tube.

6. A hopper according to claim 5, the first said member being a inner tube and the second said member being the outer sleeve.

7. A hopper according to claim 2, said inner tube being fixed against rotation and said outer sleeve being rotatable about the inner tube.

8. A hopper according to claim 2, the said openings in the two members being shaped such that upon relative rotation of the two members, the through opening 10 travels up the feed tube, closing beneath it.

9. A hopper according to claim 8, said openings comprising a pair of equal pitch opposite hand helical slots located one in each of said members.

10. A hopper according to claim 8, said openings 15 comprising a pair of equal pitch, opposite hand helical rows of openings, one row in each member, the holes in the two rows being at corresponding heights to each other.

11. A hopper according to claim 2, including a third 20 member coaxial with the outer tube and sleeve members, said third member including openings registering with the openings in at least one of the said first or second members, said third member being movable to at least partially cover the through openings while the first 25 two members are fixed relative to each other for a fine adjustment of the said through opening.

12. A hopper according to claim 2, at least one of 30 said inner tube or sleeve members being movable axially relative to the other for fine adjustment of the said through opening.

13. A hopper according to claim 2, the openings in 35 a first of said members comprising a plurality of openings arranged in a helical path about that member, the openings in the second member being a diverging slot, one edge of the slot diverging at an angle less than the angle of said helix so that upon relative rotation of the members, first the lower opening and then successive upper openings of the first member cross said one edge to form through openings, the slot diverging downwardly and outwardly a sufficient amount such that as each successive opening crosses said one edge and hence forms a through opening, those openings below it remain exposed through the slot to form lower through openings.

14. A hopper comprising means defining an enclosed chamber, pump means for creating a vacuum pressure within the hopper chamber, a feed tube extending downwardly into the hopper chamber to a lower end portion open to the interior of the hopper chamber, such that the vacuum pressure is communicated into the feed tube to move material therethrough into the hopper chamber, whereby when the said material in the hopper chamber rises to a level to cover the open end portion, the material blocks the vacuum pressure from the feed tube to terminate movement of the material therethrough to the hopper chamber, said feed tube including, at said lower end portion, an inner tube and an outer sleeve coaxial with the inner tube, each of said tube and sleeve including lateral openings in the sides thereof and one of said tube or sleeve being rotatable about the axis of the feed tube relative to the other, the lateral openings in the inner tube and sleeve being positioned such that at a first relative position of the inner tube and sleeve the respective openings overlie each other to form a lateral through opening through the side of the feed tube to communicate the vacuum pressure within the hopper chamber into the feed tube, and

upon relative rotation of the inner tube and the sleeve from the said first position, the upper edge of the lateral through opening moves upwardly along the feed tube to permit a higher level of material to be delivered to the hopper chamber before the material covers the opening from the hopper chamber to the feed tube.

15. A hopper according to claim 14, said inner tube and sleeve comprising feed tube members, one of said members comprising at least one slot diverging from an upper edge to a lower end at the lower end of that member, and the opening in the other member comprising a slot extending from an upper edge to the lower end of that member at a divergence angle less than that of the first said member, such that when the two members are turned relatively to overlap the slots, the upper extent of the through opening moves upwardly away from the lower end while the opening remains open

5

10

below said upper extent.

16. A hopper according to claim 14, said inner tube and outer sleeve comprising feed tube members, the opening in a first of said members comprising a plurality of openings arranged in a helical path about that member, and the opening in the second member being a diverging slot, one edge of the slot diverging at an angle less than the helical angle so that upon relative rotation of the members, first the lower opening and then successive upper openings of the first member cross said one edge to form through openings, the slot diverging downwardly and outwardly a sufficient amount such that as successive openings cross said one edge and hence form through openings, those openings below it remain exposed through the slot to form lower through openings.
